US00D814058S

(12) **United States Design Patent** (10) **Patent No.:** **US D814,058 S**
(45) **Date of Patent:** **** Mar. 27, 2018**

(54) **TRIM REVEAL EXTRUSION**

(71) Applicant: **EASYTRIM REVEALS INC.**, Calgary (CA)

(72) Inventor: **Joshua George Singh**, Calgary (CA)

(73) Assignee: **EASYTRIM REVEALS INC.**, Calgary, AB (CA)

(**) Term: **15 Years**

(21) Appl. No.: **29/567,890**

(22) Filed: **Jun. 13, 2016**

Related U.S. Application Data

(62) Division of application No. 13/194,451, filed on Jul. 29, 2011, now Pat. No. 9,366,040.

CLAIM

The ornamental design for a trim reveal extrusion, as shown and described.

DESCRIPTION

FIG. 1 is a perspective view of a trim reveal extrusion showing my new design; and,

FIG. 2 is an end elevational view thereof.

In FIG. 1, the broken lines represent environmental structures and form no part of the claimed design. In FIG. 2, the broken lines represent unclaimed portions of the claimed design.

1 Claim, 1 Drawing Sheet
